Inventor

Benjamin J. Mayo,

By Drake & Co Clty's.

UNITED STATES PATENT OFFICE.

BENJAMIN J. MAYO, OF NEWARK, NEW JERSEY.

DESIGN FOR A SPOON.

SPECIFICATION forming part of Design No. 21,175, dated November 17, 1891.

Application filed April 22, 1891. Serial No. 390,048. Term of patent 3½ years.

To all whom it may concern:

Be it known that I, BENJAMIN J. MAYO, a citizen of the United States, residing at Newark, in the county of Essex and State of New Jersey, have invented and produced a new and original Design for Spoons; and I do hereby declare the following to be a full, clear, and exact description of the invention, such as will enable others skilled in the art to which it applies to make and use the same, reference being had to the accompanying drawing, and to letters of reference marked thereon, which form a part of this specification.

The figure in the accompanying drawing is a plan showing the newly-designed spoon, the concave face of the bowl being uppermost.

The leading feature of the design consists in the spoon shaped and ornamented as will now be described.

A in the drawing indicates the bowl of the spoon, which is approximately oval in outline and concave on the upper side. B is the handle disposed at one side of the bowl. The handle is narrow toward the bowl and gradually widens out toward the opposite end, as shown. The concave face of the bowl of the spoon presents an ornamental figure of a

many-storied building with a peaked roof *c*, the sides of which have straight pitches. At the corners straight vertical buttresses *a a* appear, which terminate in conical roofs *b b*. Between said buttresses, at the front, are three arched windows, above which is a straight horizontal coping or cornice, and above this is a row of windows. Above these said windows, at the verge of the roof between the conical roofs, are three gables *d*. At the sides of the building are shown similar windows, cornices, and buttresses. The building appears to rest on the ground *e*, and *f* is the concave background, at the center of which approximately the ornament is disposed.

What I claim is—

The design for a spoon, as herein shown and described.

In testimony that I claim the foregoing I have hereunto set my hand this 14th day of April, 1891.

BENJ. J. MAYO.
